UNITED STATES PATENT OFFICE.

MICHAEL A. W. LOUIS, OF WASHINGTON, DISTRICT OF COLUMBIA.

CALENDERING-MACHINE.

SPECIFICATION forming part of Letters Patent No. 275,676, dated April 10, 1883.

Application filed March 7, 1883. (No model.)

To all whom it may concern:

Be it known that I, MICHAEL A. W. LOUIS, of Washington, in the District of Columbia, have invented certain new and useful Improvements in Calendering-Machines; and I do hereby declare that the following is a full, clear, and exact description thereof.

My invention relates to machines for drying and calendering printed paper; and it consists in certain attachments for guiding the sheets from the calendering-rolls to the discharge-table, as will be fully described hereinafter.

In the drawings, Figure 1 is a side view of my attachments applied to a calendering-machine, which latter is shown in dotted lines. Fig. 2 is a perspective view of one of my attachments. Figs. 3 and 4 are details, and Fig. 5 illustrates a slightly modified form of my device.

A A' are the calendering-rolls, similar in arrangement to those in patent to Henry J. Gill, May 11, 1875, No. 163,180.

B B' are rods that extend from one side of the machine to the other, and lie just below the adjacent faces of the rolls A A'. These rods are geared or belted to the machinery by which the rollers A A' are revolved, so that the roll A and rod B will revolve in one and the same direction, while the roll A' and rod B' will revolve in the opposite direction. The rods B B', like similar rods in the Gill patent, are provided with circular brushes, and as they turn in opposite directions the brushes grasp the paper C between them and draw it down over the roll A' and from between it and the roll A; and heretofore these brushes have delivered the paper onto a hinged rack having fingers that were supposed to guide it (the paper) on its way to the delivering-apron; but, having found that this rack performed its office imperfectly, I conceived the idea of connecting the shafts B' and c by an apron composed of endless tapes, each one of which depends from a groove in a loose collar, b, on shaft B' down to and around the shaft c, and in this way I provide a bridge or carrier that will support the paper from the time it leaves the brushes until it reaches the delivering-apron; and to care for it then I provide rollers F, that take the paper as it leaves the apron E and press it down upon the delivering-apron as it passes onto the delivery-table.

To make the action of the tapes E more certain I may provide another apron, E', that, like apron E, is composed of endless tapes. These 55 tapes encompass the rods B B', and are shown in Fig. 5, and lie so close to the tapes E as to clamp the paper between the two aprons, and consequently the paper cannot rumple or be drawn out of its course by the electricity, which generally creates so much disturbance in this class of machines, especially in winter.

The apron E' may be dispensed with with very good results; but where it is used it will be necessary to set the rod c farther back, so 65 as to leave room for the rod B' between the apron E and the reservoir G, all as shown in Fig. 5. I propose to make the bearings of all the rollers adjustable.

To guide the paper from the apron E to the delivery-apron D, I provide rollers F, one of which, with its hanger, I will now describe. F' is the roller-bracket, having jaws F², one of which is made removable; or it may be hinged to the bracket to admit of the removal and 75 replacement of the roller, and in these jaws the axle of the roller F has its bearings. The rear end of the bracket, or that opposite the jaws F², has a round threaded extension, which carries a nut, F⁴, channeled, as shown, to take 80 the arms H² of the bifurcated flange on outer end of the horizontal portion H of the hanger that suspends the bracket F' in position. The hanger is composed of a vertical and a horizontal portion or strap, and the lower end of 85 the vertical portion H' is squared out where it joins the horizontal portion to allow the bracket F' to pass through it, so as to lie along the entire length of the horizontal portion H, the curved inner end of which lies up under a 90 shoulder, f, in bracket F', so as to be out of the way and not be liable to impede the progress of the paper as it leaves the roller F, or to catch it should it curl up, and as the arms H² of the portion H of the hanger engage with the channel in the nut F⁴ the bracket may be adjusted 95 back and forward by turning the nut F⁴. The portion H' of the hanger has a flange, h, that carries a set-screw, i, and has a strap, the top of which is flanged, as at h². The main portion of strap h' is slotted at j to receive a set-screw, j², by which it is secured to the portion H of the hanger, and at j' to take a steadyng-pin that projects out from the portion H'. The 100

flange h is designed to take under the rim g of the reservoir, and the flange h^2 to take over it, and the hanger is tightened in place by the set-screw i . Now, the bracket may be adjusted up 5 and down by loosening set-screw j^2 and manipulating set-screw i , or by the turning of a set-screw, k , which, passing down through the outer portion of the bracket F' , rests upon the strap H .

The adjustability of my roller F adapts it for 10 paper of varying thicknesses and machines of varying sizes.

I may in some instances use only one roller F , but prefer to use two or more.

I do not confine myself to the precise construction herein described.

The rollers F are to be made of vulcanized rubber, glass, or any other non-conducting material.

What I claim as my invention, and desire to 20 secure by Letters Patent, is—

1. The combination, with the brush-rods of a paper drying and calendering machine, of an endless apron leading from one of them down

to the inner supporting rod of the delivery-apron, as set forth.

25

2. The combination, with one of the brush-rods, of an endless apron leading from it to the inner rod of the delivery-table, and a roller suspended above the delivery-apron, as set forth.

30

3. The combination, with rods B , B' , B^2 , and c , of endless aprons E , E' , and D , as set forth.

4. In combination with the roller F , an adjustable bracket and hanger, as set forth.

5. The roller F and its bracket, in combination with the hanger H H' , made adjustable, as 35 set forth.

6. The bracket having reduced screw-threaded end, in combination with the hanger having horizontal portion flanged at H^2 , as set forth.

In testimony that I claim the foregoing I 40 have hereunto set my hand, on this 5th day of March, 1883, in the presence of two witnesses.

MICHAEL A. W. LOUIS.
